DESIGN FOR AN AUTOMOBILE TRUCK

Robert E. Billings, City Island, N. Y., assignor to Richfield Oil Corporation of New York, New York, N. Y.

Application October 12, 1934, Serial No. 53,595

Term of patent 7 years

To all whom it may concern:

Be it known that I, Robert E. Billings, a citizen of the United States, residing at No. 477 King Avenue, City Island, in the county of Bronx and State of New York, have invented a new, original,
and ornamental Design for an Automobile Truck,
of which the following is a specification, reference being had to the accompanying drawing, forming part thereof.

Figure 1 is a front perspective view of the automobile truck, showing my new design.

Figure 2 is a rear perspective view of the automobile truck.

I claim:

The ornamental design for an automobile truck
as shown.

ROBERT E. BILLINGS.
